F. A. FULLER

BAG FASTENER

Filed July 28, 1921

Inventor
Franz A. Fuller
By his Attorney *Fred C. Lischer*

UNITED STATES PATENT OFFICE.

FRANZ A. FULLER, OF NEWARK, NEW JERSEY, ASSIGNEE TO THE J. E. MERGOTT CO.,
OF NEWARK, NEW JERSEY, A CORPORATION OF DELAWARE.

BAG FASTENER.

Application filed July 28, 1921. Serial No. 488,222.

To all whom it may concern:

Be it known that I, FRANZ A. FULLER, a citizen of the United States, residing at Newark, in the county of Essex and State 5 of New Jersey, have invented new and useful Improvements in Bag Fasteners, of which the following is a specification.

The main object of this invention is to produce a fastening device applicable to the 10 hingedly connected, metal frames of hand bags and like receptacles, whereby the same are efficiently held when in a closed condition, or separated for access to the interior of the bag in a ready manner.

15 A further object is to provide a bag fastener of unusual simplicity, two parts and a single spring comprising the entire structure.

Another purpose is in the provision of a 20 fastener of neat appearance, devoid of objectionable projections, that can be cheaply produced and easily applied.

Still another object of the invention resides in the provision of means for retaining 25 the proper alinement of the keeper and latch elements so that when the bag frame is closed, any inequalities in the frame will not interfere with the proper operation of the latch in retaining the frame elements 30 securely closed.

These and other like objects which will become evident as the description progresses, are attained by the novel design, construction and arrangement of parts 35 hereinafter described and shown in the accompanying drawing, forming a material part of this disclosure, and in which:—

Figure 1 is a top plan view showing portions of a conventional bag frame and a fastener, made in accordance with the invention, applied thereto.

Figure 2 is an enlarged bottom plan view showing the appearance of the fastener as assembled to one of the frame elements.

45 Figure 3 is a similar underside view of the fastener as assembled in detail.

Figure 4 is a perspective view of the outer or casing element of the fastener looking from the lower side thereof.

50 Figure 5 is a perspective view of the inner element prior to assembling.

Figure 6 is a transverse sectional view approximately at the center of the frame, showing the parts assembled and the frame

closed, the view being drawn to an enlarged 55 scale.

Figure 7 is a similar sectional view taken to one side of the center and showing a modification in construction.

Stated in general terms this fastener device consists of two sheet metal parts, each 60 easily formed by stamping or press operations, and readily assembled on a frame to which they are securely held by integral fastenings, no screws, rivets, or similar extraneous fastening being required.

The device, which presents unusual strength combined with neatness of appearance, is easily manipulated in locking or unlocking the bag and its use, unlike common 70 forms of snap fastenings, produces no strain on the frame or its joints.

Referring in detail to the drawing, the 75 numeral 10 designates one of the bag frame elements and 11 the other, these elements being as usual of the channel type of construction, having relatively flat meeting faces and are connected at their angularly bent, parallel terminals by pivots in the manner of hinges as is common.

One of these frame elements, as 11, contains, in the bight of its loop, a pair of spaced openings receptive of prongs 12 formed on the edge of a keeper bar 13, the 85 prongs being clinched and upset in the manner of rivets holding the keeper rigidly extended longitudinally at the center of the frame element as shown in Figures 1 and 6.

The other frame element 10 is pierced to produce a pair of slots 14 positioned in a 90 similar manner, the slots being relatively widely spaced, and adjacent one of these slots, close to the meeting face of the frame, is a shorter slot 15.

The outer element or casing of the fastener comprises a substantially flat rectangular plate 16 having a shorter, forwardly projecting, slightly depressed extension 17. The ends 18 of the plate are bent at right angles and also the front edges 19, which 100 are curved to blend into the extension 17.

In a similar manner the rear edge is bent to produce a wall 20 on which are formed projections 21, the corners 22 at one end being bevelled and their opposite corners 23 105 extended to overhang, forming in effect prongs, which, together with the main portion of the extensions are passed through

the slots 14 in the frame element 10 and ultimately clinched against the inner surface of the channel, rigidly securing the casing thereon.

- 5 The front edge of the extension 17 is curved lengthwise as at 24, the material being bent back under the extension, as at 25, and its end edges 26 prolonged nearly to the wall 20, leaving an open space 27 therebetween. These prongs 26 form guides so that when the bag frame is closed, the keeper 13 will be properly guided into the space between the prongs 26 and against the edge 27 of the latch element in such manner as to cause said edge 27 to wholly engage the side face of the keeper.

Obviously such structure will insure the proper closing and securing of the frame though said frame may become bent or sprung out of shape through usage.

10 The other element of the fastener comprises a plate 28, disposed when assembled on the plate 16 in register with the opening 27 and having a raised bevelled extension 25 29 protruding between the inner surfaces 17 and 25.

15 Stepped extensions 30 and 31 are formed at the ends of the plate 28, the same projecting slightly beyond the corresponding edge of the plate 28 and having their opposite edges aligned with the edge 29. These steps lead to end plate elements 32 and 33 disposed in a plane raised from the steps 30 and 31, and having their rear edges 35 bent at right angles forming walls 34, their opposite edges being similarly formed into walls 35.

20 The walls 34 and 35 are so spaced apart as to closely enter the box-like structure of the casing which also receives the ends of the elements 32 and 33 when assembled.

25 The corner of the step 32 and part of the wall 34 is removed, leaving an opening 36. Also in the edge 29 and adjacent step 31 is a recess 37, the purposes of which will now be described.

30 A piece of spring wire is bent to produce an angular end 38 extending out through the corner opening 36 and into the slot 15 of the frame element 10 when assembled, the body or main portion 39 of the wire being disposed between the two elements of the fastener, past the retracted edge 40 of the plate 28 and turned at a right angle 40 under the step 31 and then bent reversely, the terminal portion 41 passing out of the recess 37, below the projection 26 at its juncture with the rear wall 20, thus forming a torsional spring.

35 In the modification shown in Fig. 7, the prongs 22 and 23 are omitted, the wall 20 coming squarely into contact with the outer surface of the channel, prongs 42, similar in all respects, being formed directly on the elements 32 and 33, the same extending oppo-

sitely from walls 34, or in other words, the walls 34 are bent in an opposite direction to that shown in Figure 5, and formed into prongs.

40 In assembling, the casing element is formed so that the parts 24 and 25 extend at an angle, as shown in Fig. 4, the inner element and spring entered and the parts 24 and 25 closed over them.

45 This brings the elements 32 and 33 substantially flush and level with the elements 26 and 27, presenting a smooth surface except for the extending end 38 of the spring, which is then entered into the slot 15, the prongs 21, 23 or 42 being simultaneously entered into the slots 14 and moved so that their overhanging portion will engage the inner surface of the channel 10, whereupon the hook portions 23 are bent down to prevent removal. The elements 21, 22 and 23 are however relatively narrower than the slots and therefore permit the fastener to move with a swinging motion within limits, but prevent its removal.

50 In operation, due to the torsional effect of the spring, the fastener is normally pressed into such position that its under surface is at a right angle with the meeting faces of the frames, and when brought into forcible contact with the keeper 13, will rise to pass over it and cause it to engage the outer edge of the opening 27, thus locking the frame members together.

55 It will be clearly seen that owing to the projection of the prongs 26 beyond the edge 27, a pocket or recess will be formed in the latch element which will wholly embrace the keeper and effectively aline the frame elements even though the same may have become sprung or bent out of shape.

60 Obviously to separate the same, the fastener is manually raised to clear the keeper and the parts separated by hand in the usual manner.

65 Although the foregoing is descriptive of the preferred embodiment of the invention, it will be apparent that minor changes may be made in its construction, without the exercise of invention or conflicting with the scope of the claims hereto appended.

70 Having thus described my invention, what I claim as new and desire to secure by Letters Patent, is:—

75 1. In a bag fastener, the combination with a pair of frames, one having a raised keeper and the other containing a pair of spaced slots and an opening, of a fastener comprising a box-like casing having an extension, said extension presenting a curved outer longitudinal edge, a plate held in said casing, a spring disposed between said plate and casing, said spring having its end engaged in the mentioned frame opening, means in said fastener for engaging said keeper, and means formed with said fas-

tener engageable in the slots of said frame, said means permitting a limited swinging movement of said fastener, but preventing its removal.

- 5 2. A bag fastener comprising a hollow casing, a stepped plate held therein, a torsional spring disposed between said plate and casing, said spring having a single extending end adapted to engage one member
10 of a bag frame, spaced prongs on said casing adapted to enter slots in the frame, means for securing said prongs after assembly, said prongs permitting a limited swinging motion to said casing, and means
15 formed with said casing adapted to engage a keeper on the other member of the bag frame.
3. A bag fastener comprising in combination with a pair of frames, one of said

frames having a keeper and the other containing perforations, an elongated casing having a front extension, a stepped plate held in said casing presenting a level under surface, means on the fastener engaging certain of the mentioned perforations whereby it may be limitedly turned outwardly, means in the fastener engageable with said keeper, and a single torsional spring operatively engaging the other of the mentioned perforations and the fastener whereby such engagement is normally effected.

This specification signed and witnessed this 14th day of July, 1921.

FRANZ A. FULLER.
